Middlesex, England, a company of Great
Britain

Application April 15, 1948, Serial No. 21,136
In Great Britain April 18, 1947

9 Claims. (Cl. 313—104)

1

This invention relates to discharge devices employing secondary-electron-emission.

Various proposals have been made heretofore for the construction of so-called multi-stage electron discharge devices employing secondary-electron-emission, comprising a thermionic cathode for emitting a beam of primary electrons, a control electrode whereby the thermionic emission from said cathode can be controlled, a secondary-electron-emitting electrode (hereinafter and in the claims referred to for convenience as a dynode) on which said beam of electrons can be caused to impinge so as to release secondary electrons, at least one further dynode on which said secondary electrons can be caused to impinge so as to release further secondary electrons, and a collecting electrode for collecting secondary electrons released from said latter dynode. Electron discharge devices of this kind are referred to hereinafter and in the claims as devices of the kind described.

Such devices would be particularly suitable for use as amplifying valves, the signals to be amplified being applied to said control electrode and an amplified output of said signals being obtained at said collecting electrode. However the devices which have been proposed hitherto have given rise to constructional and electron-optical difficulties and the object of the present invention is to provide an improved electron discharge device of the kind described with a view to reducing these difficulties.

According to the present invention an electron discharge device of the kind described is provided, wherein said first dynode comprises a secondary-electron-emitting surface which is located beyond said second dynode when viewed from said thermionic cathode, and wherein the electrodes in said device are so arranged that when appropriate potentials are applied thereto a beam of primary electrons is projected from said thermionic cathode at an acute angle to a plane containing said cathode and said second dynode whereby said beam is caused to pass substantially wholly to one side of said second dynode and impinge on said first dynode.

In order that the said invention may be clearly understood and readily carried into effect, the same will now be more fully described with reference to the accompanying drawings, in which—

Figure 1 is a transverse sectional view of an electron discharge device according to one embodiment of the present invention.

Figures 2 and 3 illustrate modifications of said embodiment, and

2

Figure 4 is a transverse sectional view according to another embodiment of the present invention.

Referring first to Figure 1 of the drawings, reference numeral 1 indicates a thermionic cathode which is of elongated form having a rectangular transverse section as shown in the drawings, the wider sides of the cathode being electron-emissive. Surrounding the cathode 1 is a control electrode 2 which is a wire-wound electrode supported by support rods 3 and surrounding the control electrode is an accelerating electrode 4 which is also a wire-wound electrode supported by support rods 5. Surrounding the electrode structure so far described is a dynode 6 which is preferably in the form of a continuous sheet of metal shaped so that it is elliptical in transverse section as shown, the major axis and the minor axis of the ellipse being indicated by the chain dotted lines 20 and 21 respectively so that the longitudinal axis of the dynode is represented by the intersection 22 of the axes 20 and 21, said last mentioned axis being of course normal to the plane of the drawing. The inner surface of said dynode 6 is provided with a coating of secondary-electron-emitting material indicated by the dotted lines 6a. The coating may be such as is described in British Patent No. 601,966 and is provided on areas adjacent to the ends of the major axis 20 on opposite sides thereof. Disposed within the elliptical dynode 6 and near the ends of the major axis 20 is a pair of further dynodes 7 and 8, these dynodes 7 and 8 being located on either side of the cathode 1, as shown and being preferably in the form of tubes having a circular cross-section and also coated on their surfaces, where electrons emitted by the electrode 6 impinge, with secondary-electron-emitting material. Surrounding the dynodes 7 and 8 are anodes 9 and 10 which are preferably helices wound from wire and supported by support rods 11 and 12, and between the dynodes 7 and 8 and the cathode 1 there are disposed focussing electrodes 13 and 14 which are in the form of rod-shaped electrodes. The electrode structure is, as stated, shown in transverse section in Figure 1 and it will be appreciated that the length of the various electrodes in a plane normal to that of the drawing may be of any desired length. The dynodes 7 and 8 and the focussing electrodes 13 and 14 are disposed with their longitudinal axes in the plane containing the longitudinal axis 22 and also the major axis 20 of the elliptical dynode 6, said plane being normal to the plane of the drawing. This latter

plane also contains the common longitudinal axis of the cathode 1, control electrode 2 and accelerating electrode 4. Moreover these latter electrodes, in transverse section as shown, have a common major axis 23 and a common minor axis 24 and said major axis is disposed at an angle with respect to the major axis of the elliptical dynode 6 of not less than 20° and not greater than 70°, the preferred inclination being 40°, this being the inclination shown in the drawings. The electrode structure is arranged in usual manner in a suitable evacuated glass envelope 15.

In operation of the discharge device shown, the cathode may be maintained at earth potential, the control electrode 2 at a suitable negative potential so that signals applied to the control electrode cause a variation in the thermionic emission from cathode 1. The accelerating electrode 4 may be maintained at a positive potential of about 150 volts, the dynode 6 at a positive potential of about 250 volts, the dynodes 7 and 8 at positive potentials of about 400 volts and the anodes 9 and 10 at positive potentials of about 600 volts. The electrodes 13 and 14 may be maintained at the potential of the cathode 1 or at the potential of the electrode 4. On applying these potentials to the electrodes, primary electrons are emitted from the wider sides of the cathode 1 in the form of oppositely directed beams, which are fairly well defined as indicated by the dotted lines, each beam being projected at an acute angle (about 50° in this example), to the plane containing the longitudinal axes of the cathode 1, and the dynodes 7 and 8. After leaving the cathode 1 the beams are deflected by the combined field due to the anodes 9 and 10 and the dynodes 7 and 8, but the angle at which they leave the cathode 1 is nevertheless such that they are caused to pass substantially wholly to one side of the respective dynodes 7 and 8 and impinge on the surface of the dynode 6 near the anodes 9 and 10 as shown, the electron-emitting surfaces of the dynodes 6 as seen from the cathode 1 being of course located beyond the dynodes 7 and 8. The sides of the beams nearer the anodes 9 and 10 are prevented from being deflected and so impinging on said anodes and the dynodes 7 and 8 by means of the electrodes 13 and 14. The primary beams of electrons release secondary electrons from the dynode 6 and these secondary electrons are then caused to impinge on the further dynodes 7 and 8 from which further secondary electrons are emitted which are collected by the anodes 9 and 10.

It is preferred to make the shape of the dynode 6 elliptical, as shown, since the areas thereof from which secondary electrons are emitted are thereby brought closer to the anodes 9 and 10. The shape of the anodes 9 and 10 in transverse section where they face the areas from which secondary electrons are emitted from the dynode 6 are preferably circular, as shown, so that the secondary electrons emitted by the dynode 6 pass substantially normally through the anodes 9 and 10 on to the dynodes 7 and 8. The capacity between the anodes 9 and 10 and the control electrode 2 is substantially eliminated by the provision of channel-shaped shields 16 disposed adjacent the accelerating electrode 4, and attached to the focussing electrodes 13 and 14, as described in the specification of the aforesaid co-pending application. The shields 16 may however, if desired, be attached to the accelerating electrode 4, instead of the focussing electrodes.

The cathode 1 preferably has the rectangular transverse section shown, but may, if desired, be of elliptical form in transverse section as illustrated in Figure 2 in which case the electrodes 2 and 4 may also be elliptically-shaped in transverse section as illustrated. It may, in some cases, be possible to employ a cathode of circular form in transverse section as illustrated in Figure 3. In this case in order to concentrate the electrons emitted from the cathode 1 so as to form two oppositely directed beams at an acute angle to the plane containing the longitudinal axes of the cathode 1 and the dynodes 7 and 8, the control electrode 2 and the accelerating electrode 4 have, in transverse section, a major axis and a minor axis with the supporting rods 3 and 5 disposed on the major axis and with the major axis inclined at an acute angle to said plane, while two channel-shaped beam-forming electrodes 17 and 18 are provided adjacent opposite ends of said major axis. By suitably varying the inclination of the electrodes 2, 4, 17 and 18 it should be possible to avoid the risk of the beams from the circular cathode impinging on the anodes 9 and 10.

An electron discharge device with the electrode structure shown in Figure 1 has the disadvantage that the leads required to connect the dynodes 7 and 8 together, and the anodes 9 and 10 together, will be of considerable length. In order to reduce the length of leads required the electrode structure shown in Figure 4 may be employed. In this figure electrodes which correspond to those shown in Figure 1 are given the same reference numerals. The electrode structure shown in Figure 4 is a development of that shown in Figure 1 and is obtained by replacing one-half of the electrode structure shown in Figure 1 by the mirror image of the remaining half taken along the plane containing the longitudinal axis and also the major axis 23 of the electrodes 1, 2 and 4, said plane being of course substantially normal to the directions in which the oppositely directed beams leave the cathode 1. The dynode 6 therefore comprises a structure each half of which conforms in cross section to part of an elliptical surface whose major axis is inclined to the major axis of the other half, the major axis of the halves being indicated respectively by the chain dotted lines 25 and 26. It will be observed from Figure 4 that the anodes 9 and 10 are thus disposed closer together and near to one edge of the screening electrode 4. Hence, the length of the leads required to connect the dynodes 7 and 8 together and the anodes 9 and 10 together can be made shorter, thus reducing the inductance of the leads and resulting in a simplification in the structure of the device in so far as concerns the screening of the anode leads and the lead to the control electrode 2 from one another. In Figure 2, only a single channel section screen 15 is employed, instead of two as in Figure 1, attached to the focussing electrodes 13 and 14, as shown or, if desired to the screening electrode 4.

I claim:

1. In a multi-stage electron discharge device which utilises secondary electron emission for obtaining amplification, a thermionic cathode, a control electrode for controlling thermionic emission from said cathode, a first dynode comprising a structure conforming to a closed curved surface, a second dynode, said thermionic cathode and said second dynode being enclosed by said surface, an electrode for collecting secondary elec-

trons from said second dynode, and means for projecting the electrons released from said cathode in a beam at an angle to pass substantially wholly to one side of said second dynode and impinge on the inner side of said first dynode, whereby to release secondary electrons which can impinge on said second dynode.

2. In a multi-stage electron discharge device which utilises secondary electron emission for obtaining amplification, a thermionic cathode, a control electrode for controlling thermionic emission from said cathode, a first dynode comprising a structure conforming to at least part of a surface of substantially elliptical cross section, said structure provided with secondary electron emissive material on an area on the inner side adjacent one end of the major axis of said surface, a second dynode enclosed by said surface and intersected by the plane containing said major axis and the longitudinal axis of said surface, said cathode being also enclosed by said surface and intersected by said plane on the other side of said second dynode from said end of the major axis, an electrode for collecting secondary electrons from said second dynode, and means for projecting electrons released from said cathode in a beam at an acute angle to said plane to pass substantially wholly to one side of said second dynode and impinge on said area, whereby to release secondary electrons which can impinge on said second dynode.

3. In a device according to claim 2, said cathode comprising a tubular member having in cross section a major axis and a minor axis, the longitudinal axis of said cathode member being disposed in said plane while the major axis of said cathode member is disposed at an angle to said plane of 20 to 70 degrees.

4. In a device according to claim 2, said beam projecting means comprising an electrode structure having in cross section a major axis and a minor axis, the longitudinal axis of said structure being disposed in said plane while the major axis of said structure is disposed at an angle to said plane of 20 to 70 degrees.

5. In a device according to claim 2, said beam projecting means comprising an electrode structure having in cross section a major axis and a minor axis, the longitudinal axis of said structure being disposed in said plane while the major axis of said structure is disposed at an angle to said plane of 20 to 70 degrees.

6. In a device according to claim 5, the major axis of said structure being disposed at an angle of about 40 degrees to said plane.

7. In a multi-stage electron discharge device which utilises secondary electron emission for obtaining amplification, a thermionic cathode, a control electrode for controlling thermionic emission from said cathode, a first dynode comprising a structure conforming to a surface of substantially elliptical cross section, said structure having secondary electron-emissive material provided on two areas on the inner side respectively adjacent and on opposite sides of the ends of the major axis of said structure, a second dynode comprising two structures located respectively adjacent said areas and intersected by the plane containing the major axis and the longitudinal axis of said first dynode structure, said thermionic cathode and said second dynode struc-

tures being enclosed by said first dynode structure and said cathode being located between said second dynode structures, an electrode for collecting secondary electrons from said second dynode structures, and means for projecting electrons emitted from said cathode in oppositely directed beams at an angle to pass, respectively, substantially wholly to one side of said second dynode structures and impinge on said areas, whereby to release secondary electrons which can impinge on said second dynode structures.

8. In a multi-stage electron discharge device which utilises secondary electron emission for obtaining amplification, a thermionic cathode, a control electrode for controlling thermionic emission from said cathode, a first dynode comprising a structure one half of which is a mirror image of the other half and conforms to part of a surface of substantially elliptical cross section whose major axis is inclined to the major axis of the other half, said structure being provided with electron emissive material on the inner side of each half adjacent the end of the corresponding major axis, a second dynode comprising two structures disposed respectively within the halves of said first dynode structure whereby each of said second dynode structures is intersected by the plane containing the major axis and the longitudinal axis of the corresponding half of the first dynode structure, said cathode being located at the intersection of said planes, an electrode for collecting secondary electrons from said second dynode structures, and means for forming electrons emitted from said cathode into oppositely directed beams projected at an angle to pass, respectively, wholly to one side of said dynode structures and impinge on said areas whereby to release secondary electrons which can impinge on said second dynode structures.

9. In a multi-stage electron discharge device which utilises secondary electron emission for obtaining amplification, a thermionic cathode, a control electrode for controlling thermionic emission from said cathode, a first dynode and a second dynode, said first dynode being located beyond said second dynode when viewed from said cathode and comprising a structure curved in cross section to be concave towards said second dynode, said second dynode comprising an elongated member of smaller area than said first dynode, a collecting electrode previous to electrons surrounding said second electrode, and means for projecting electrons released from said cathode in a beam at an angle with reference to said second dynode to pass substantially wholly to one side of said second dynode and impinge on said first dynode whereby to release secondary electrons which converge on said second dynode.
